UNITED STATES PATENT OFFICE.

GEORGE O. DRAPER, OF HOPE DALE, MASSACHUSETTS, ASSIGNOR TO THE DRAPER COMPANY, OF SAME PLACE AND PORTLAND, MAINE.

DESIGN FOR A DETECTOR FOR WARP STOP-MOTIONS.

SPECIFICATION forming part of Design No. 29,500, dated October 18, 1898.

Application filed July 28, 1898. Serial No. 687,139. Term of patent 14 years.

To all whom it may concern:

Be it known that I, GEORGE O. DRAPER, a citizen of the United States, and a resident of Hopedale, in the county of Worcester and State of Massachusetts, have invented and produced a new and original Design for a Detector for Warp Stop-Motions, of which the following is a specification.

Figure 1 of the drawings shows in front elevation a detector illustrating my design; and Figs. 2 and 3 are cross-sections thereof on the lines $x x$ and $x' x'$, respectively, Fig. 1.

The leading feature of my design for a detector for warp stop-motions consists in an elongated thin body having flat parallel sides and parallel edges and a longitudinal slot therein open at one end and dividing the part of the body traversed thereby into two legs of unequal length.

The detector is shown as consisting of a thin and elongated body a , having flat parallel sides and parallel edges and a longitudinal slot a' therein open at one end, as at a^2 , the slot dividing the part of the body traversed thereby into two legs $a^3 a^4$ of unequal length.

Having fully described my invention, what I claim is—

The design for a detector for warp stop-motions, substantially as herein shown and described.

In testimony whereof I have signed my name to this specification in the presence of two subscribing witnesses.

GEORGE O. DRAPER.
